WINDING APPARATUS

Hans-Joachim Stahl and Benno Zeller, Unna, Germany, assignors to Firma Wilhelm Breitenbach, G. m. b. H., Unna, Germany

Application May 6, 1954, Serial No. 428,074

Claims priority, application Germany May 6, 1953

8 Claims. (Cl. 242—25)

The present invention relates to winding apparatus. More particularly, the present invention relates to a wire coiling apparatus adapted to coil wire or the like on a spool which may either be stationary or rotate during winding of the wire thereon.

Wire coiling devices are known which are equipped with stationary spools, as well as winding devices which have a plurality of rotatable spools driven by a common shaft. Winding apparatus equipped with stationary spools are of particular advantage in winding wire which can be wound at great speed. However, in the case of wire, such as steel wire or thick wire, which is not adapted for coiling on a stationary spool, it is necessary to use a machine having a rotating spool. It has been necessary, therefore, to utilize heretofore two different complete machines in order to coil the different types of wire.

The present invention is designed to overcome the above disadvantages and in carrying out the present invention an apparatus is provided wherein the spool is made stationary by means of a planetary gear arrangement and includes a supplementary gear arrangement to produce rotation of the spool if desired. This supplementary gear arrangement also provides for a desired direction of rotation as well as the desired speed of rotation of the spool. Finally, the coiling device of the present invention is so constructed that it may be easily put into and out of operation, and for this purpose a coupling device is provided on the shaft of the coiling apparatus.

It is an object, therefore, of the present invention to provide a coiling device which is adapted for coiling various types of wire.

It is another object of the present invention to provide a wire coiling device which may alternatively utilize a stationary or a rotating spool on which the wire is to be wound.

It is a further object of the present invention to provide a multiple wire coiling apparatus of the above type for simultaneously coiling a plurality of wires.

Other objects and advantages will become apparent from the following description and the appended claims.

The novel features which are considered as characteristic for the invention are set forth in particular in the appended claims. The invention itself, however, both as to its construction and its method of operation, together with additional objects and advantages thereof, will be best understood from the following description of specific embodiments when read in connection with the accompanying drawings, in which:

Fig. 1 is a side elevational view partly in section of a coiling apparatus constructed in accordance with the present invention;

Fig. 2 is an end view of the multiple coiling apparatus according to the present invention;

Fig. 3 is a plan view of the apparatus shown in Fig. 2;

Fig. 4 is a detailed view of a guide roller mounting incorporated in the device shown in Fig. 1;

2

Fig. 5 is a detailed end view of the coupling device shown in Fig. 1; and

Fig. 6 is a plan view of the linkage arrangement for operating the coupling device of the apparatus shown in Fig. 1.

Referring now to the drawings, and particularly to Fig. 1, there is shown a closed unitary housing 1 which serves as a carrier support for several independent coil winding machines and as shown in Fig. 3, housing 1 supports eight individual coil winding devices. The operation of all of the coil winding machines is carried out by means of a common shaft 2 journaled in housing 1, the shaft 2 adapted to be driven in any suitable manner. To this end, there is provided steel worms 3 arranged on shaft 2 spaced at particular distances. As shown in Fig. 1, steel worm 3 is arranged in engagement with a worm gear 4, which is loosely mounted on coil winding shaft 5 of the coil winding machine, while shaft 5 is rotatably mounted in housing 1 on integrally cast bearings 6 and 7.

20 A winding disc 8 is fixedly secured to shaft 5 for rotation therewith, disc 8 having at its outer periphery a link member 9 which carries a rotatable guide roller 10 and is turnable about a pivot axis, as shown in the solid and dotted lines of Fig. 1. Shaft 5 is provided with an axially extending channel 12 passing therethrough, and the wire to be wound on spool 15 is guided into channel 12 by means of guide rollers 13 and 14 arranged at one end of shaft 5, the wire being conducted out of channel 12 by means of guide roller 11 which is mounted adjacent and extends into channel 12. The mounting of guide roller 11 on shaft 5 is shown in greater detail in Fig. 4.

25 The wire thus conducted through channel 12 and around guide roller 10 is continuously wound during the rotation of disc 8 on spool 15, which remains stationary during such rotation of disc 8 by virtue of a planetary gear arrangement shown in Fig. 1. This gear arrangement includes a spur gear 16 which is fixedly mounted on bearing 7. Engaging spur gear 16 is a pinion 17 which together with pinion 18 is mounted on a common shaft 19, pinion 18 adapted to engage a spur gear 20 which is mounted for axial movement on the hub 21 of spool 15. The pinions 17 and 18 have the same pitch and the same diameter, as do the larger spur gears 16 and 20, respectively. Shaft 19 is mounted on support 29 integral with disc 8. Hub 21 is loosely mounted on coiling shaft 5 and is thereby rotatable relative to shaft 5.

30 It will be seen that as shaft 5 and disc 8 rotate together, the gear arrangement above described provides for spool 15 to remain stationary when pinion 18 engages spur gear 20.

35 Coiling of the wire can also be carried out with the same apparatus on spool 15 while the latter spool rotates by means of the planetary auxiliary gear arrangement also shown in Fig. 1. This auxiliary gear arrangement includes an additional pinion 22 mounted on shaft 19, pinion 22 being of smaller diameter than pinions 17 and 18 and being adapted to engage spur gear 23 which is fixedly mounted relative to spur gear 20 and forms together with spur gear 20 a sliding gear which is axially movable along hub 21 of spool 15. Spur gear 23 has a larger diameter than spur gear 20, so that as a result of turning of shaft 5 while spur gear 23 is in engagement with pinion gear 22, spool 15 is set into rotation.

40 By suitably changing the diameter of the gears, it is possible to vary the speed of rotation and also the direction of rotation of spool 15. The alternative engagement of gears 23 and 20 with their respective pinions can be carried out by means of a push rod 24 which is held in its different positions by means of a set screw 25. In the arrangement of the apparatus shown in Fig. 1, coiling of the wire is carried out by conducting the wire to be coiled over a guide roller 26. In this case, the guide roller 10

which is hingedly mounted on the periphery of the winding disc 8 is swung into its inoperative position as shown in Fig. 1 so as not to interfere with the moving wire.

Each of the eight coil winder machines (Fig. 3) is individually capable of being connected and being disconnected from operation. For this purpose, a coupling arrangement 27 is provided on shaft 5 which can be brought into engagement with worm gear 4 by means of a lever system 28. Lever system 28 is so arranged that the coupling and uncoupling of the coil winding machines can be carried out from the position of the operator located adjacent the spool.

As shown in Fig. 6, coupling member 27 has projecting portions 30 which are adapted to be moved into corresponding recesses 31 in worm gear 4. Coupling member 27 is axially movable along and keyed on shaft 5, being movable thereon for engagement with gear 4 by a yoke 33 riding freely in groove 34 in coupling member 27.

The multiple wire coiling apparatus of the present invention has several advantages. When the machine is operated with a stationary spool, the wire can be wound with increased speed and the wire coils can be removed without danger of injury. The apparatus according to the present invention is also suitable for winding thicker types of wire, and particularly steel wire, on a rotating spool, the spool rotating slower than the speed of rotation of the coiling disc and therefore the wire can be coiled in the range of speed of a machine which is equipped only with a rotating spool.

Each coil winding machine can be set into operation independently of the others, and it is thereby possible to coil simultaneously wire of different sizes and types on the apparatus. The planetary gear arrangement of each coil winding machine provides the correct direction of rotation and the speed of rotation, and the latter speed can be widely varied by suitable selection of the gear ratio and thereby adapt the machine to all needs. Instead of arranging the coil winding machines on both sides of the supporting housing, the machines may be arranged if desired only on one side.

The apparatus according to the invention incorporates into one device both constructions of the single coil winding machines known heretofore, without making necessary an increase in the overall dimensions of the machine.

It will be understood that each of the elements described above, or two or more together, may also find a useful application in other types of winding devices differing from the types described above.

While the invention has been illustrated and described as embodied in wire coiling apparatus, it is not intended to be limited to the details shown, since various modifications and structural changes may be made without departing in any way from the spirit of the present invention.

Without further analysis, the foregoing will so fully reveal the gist of the present invention that others can by applying current knowledge readily adapt it for various applications without omitting features that, from the standpoint of prior art, fairly constitute essential characteristics of the generic or specific aspects of this invention and, therefore, such adaptations should and are intended to be comprehended within the meaning and range of equivalence of the following claims.

What is claimed as new and desired to be secured by Letters Patent is:

1. A winding apparatus, comprising, in combination, rotatable shaft means; driving means for rotating said shaft means; spool means mounted on said shaft means rotatably relative thereto, said spool means being adapted to have a filament wound thereon; winding means mounted on said shaft means for rotation therewith adjacent to said spool means and adapted to carry a filament for winding the filament on said spool means; and transmission gear means connecting said spool means with said

shaft means, said transmission gear means including a planetary gear arrangement for holding said spool means stationary during rotation of said shaft means and an auxiliary gear arrangement for rotating said spool means during rotation of said shaft means.

2. A winding apparatus, comprising, in combination, rotatable shaft means; driving means for rotating said shaft means; spool means mounted on said shaft means rotatably relative thereto, said spool means being adapted to have a filament wound thereon; winding means mounted on said shaft means for rotation therewith adjacent to said spool means and adapted to carry a filament for winding the filament on said spool means; transmission gear means connecting said spool means with said shaft means, said transmission gear means including a first gear arrangement for holding said spool means stationary during rotation of said shaft means and an auxiliary gear arrangement for rotating said spool means during rotation of said shaft means; and shifting means for alternatively connecting said shaft means and said spool means by means of said first and said auxiliary gear arrangements.

3. A winding apparatus, comprising, in combination, rotatable shaft means; driving means for rotating said shaft means; spool means having a hub mounted on said shaft means rotatably relative thereto, said spool means being adapted to have a filament wound thereon; winding means mounted on said shaft means for rotation therewith adjacent to said spool means and adapted to carry a filament for winding the filament on said spool means; and transmission gear means connecting said spool means with said shaft means, said transmission gear means including a first gear arrangement for holding said spool means stationary during rotation of said shaft means and an auxiliary gear arrangement for rotating said spool means during rotation of said shaft means, a portion of said transmission gear means being arranged on said hub of said spool means and being axially slidably thereon for alternative operation of said first and said auxiliary gear arrangements.

4. A winding apparatus, comprising, in combination, rotatable shaft means; driving means for rotating said shaft means; spool means having a hub mounted on said shaft means rotatably relative thereto, said spool means being adapted to have a filament wound thereon; winding means mounted on said shaft means for rotation therewith adjacent to said spool means and adapted to carry a filament for winding the filament on said spool means; transmission gear means connecting said spool means with said shaft means, said transmission gear means including a first gear arrangement for holding said spool means stationary during rotation of said shaft means and an auxiliary gear arrangement for rotating said spool means during rotation of said shaft means, a portion of said transmission gear means being arranged on said hub of said spool means and being axially slidably thereon for alternative operation of said first and said auxiliary gear arrangements.

5. A multiple winding apparatus, comprising, in combination, a plurality of winding machines each including rotatable shaft means; common driving means for rotating the shaft means of each of said plurality of winding machines; coupling means for independently coupling each of said shaft means with said common driving means, said coupling means being operable for connecting and disconnecting said shaft means from said common driving means; spool means mounted on said shaft means rotatably relative thereto, said spool means being adapted to have a filament wound thereon; winding means mounted on said shaft means for rotation therewith adjacent to said spool means and adapted to carry a filament for winding the filament on said spool means; and transmis-

sion gear means connecting said spool means with said shaft means, said transmission gear means including a first gear arrangement for holding said spool means stationary during rotation of said shaft means and an auxiliary gear arrangement for rotating said spool means during rotation of said shaft means.

6. A multiple winding apparatus, comprising, in combination, a plurality of winding machines each including rotatable shaft means; common driving means for rotating the shaft means of each of said plurality of winding machines; coupling means for independently coupling each of said shaft means with said common driving means, said coupling means being operable for connecting and disconnecting said shaft means from said common driving means; spool means mounted on said shaft means rotatably relative thereto, said spool means being adapted to have a filament wound thereon; winding means mounted on said shaft means for rotation therewith adjacent to said spool means and adapted to carry a filament for winding the filament on said spool means; transmission gear means connecting said spool means with said shaft means, said transmission gear means including a first gear arrangement for holding said spool means stationary during rotation of said shaft means and an auxiliary gear arrangement for rotating said spool means during rotation of said shaft means; and shifting means for alternatively connecting said shaft means and said spool means by means of said first and said auxiliary gear arrangements.

7. A multiple winding apparatus, comprising, in combination, a plurality of winding machines each including rotatable shaft means; common driving means for rotating the shaft means of each of said plurality of winding machines; coupling means for independently coupling each of said shaft means with said common driving means, said coupling means being operable for connecting and disconnecting said shaft means from said common driving means; spool means mounted on said shaft means rotatably relative thereto, said spool means being adapted to have a filament wound thereon; elongated operating means for operating said coupling means, said operating means being operable from a position adjacent the spool

means of the respective winding machines; winding means mounted on said shaft means for rotation therewith adjacent to said spool means and adapted to carry a filament for winding the filament on said spool means; transmission gear means connecting said spool means with said shaft means, said transmission gear means including a first gear arrangement for holding said spool means stationary during rotation of said shaft means and an auxiliary gear arrangement for rotating said spool means during rotation of said shaft means; and shifting means for alternatively connecting said shaft means and said spool means by means of said first and said auxiliary gear arrangements.

8. A multiple winding apparatus, comprising, in combination, a plurality of winding machines each including rotatable shaft means; common driving means for rotating the shaft means of each of said plurality of winding machines; coupling means for independently coupling each of said shaft means with said common driving means, said coupling means being operable for connecting and disconnecting said shaft means from said common driving means; spool means mounted on said shaft means rotatably relative thereto, said spool means being adapted to have a wire wound thereon; winding disc means mounted on said shaft means for rotation therewith and extending transverse thereto adjacent to said spool means and adapted to carry a wire for winding the wire on said spool means; and transmission gear means connecting said spool means with said shaft means, said transmission gear means including a first gear arrangement for holding said spool means stationary during rotation of said shaft means and an auxiliary gear arrangement for rotating said spool means during rotation of said shaft means.
